DESIGN FOR A VAPORIZER

Walker L. C. Huxter, Richmond, Va.

Application October 3, 1938, Serial No. 80,232

Term of patent 14 years

To all whom it may concern:

Be it known that I, Walker L. C. Huxter, a citizen of the United States, residing at Richmond, in the county of Henrico and State of Virginia, have invented a new, original, and ornamental Design for Vaporizers, of which the following is a specification, reference being had to the accompanying drawing, forming part thereof.

Figure 1 is a perspective view of a vaporizer, showing my new design;

Figure 2 is a side view of the same vaporizer; Figure 3 is a similar side view, the vaporizer being rotated 90° with respect to the position shown in Figure 2; and

Figure 4 is a bottom plan view of the same vaporizer.

I claim:

The ornamental design for a vaporizer, as shown.

WALKER L. C. HUXTER.
